PHOTOELECTROSTATIC COPYING APPARATUS

Robert Louis Deschamps, West Chicago, Ill., assignor to
Addressograph-Multigraph Corporation, Mount Pros-
pect, Ill., a corporation of Delaware

Filed June 9, 1965, Ser. No. 85,650

Term of patent 14 years

(Cl. D61—1)

Fig. 1

Fig. 2

Fig. 3.

Fig. 4.

FIGURE 1 is a perspective view showing the front and right side panel of a photoelectrostatic copying apparatus, showing my new design;

FIGURE 2 is a top plan view thereof;

FIGURE 3 is a front elevation thereof; and

FIGURE 4 is a perspective view thereof, showing the back and left side.

I claim:

The ornamental design for a photoelectrostatic copying apparatus, substantially shown.
